(57) **CLAIM**

The ornamental design for an aerator, as shown and described.

DESCRIPTION

FIG. 1 is a front, top and left perspective view of an aerator showing my new design;

FIG. 2 is a rear, bottom and right perspective view thereof;

FIG. 3 is a front elevational view thereof;

FIG. 4 is a rear elevational view thereof;

FIG. 5 is a top plan view thereof; and,

FIG. 6 is a bottom plan view thereof.

FIG. 7 is a left side elevational view thereof;

FIG. 8 is a right side elevational view thereof; and,

FIG. 9 is an enlarged view of the portion indicated by line

9 in FIG. 1.

The dash-dash broken lines in the drawings depict portions of the aerator that form no part of the claimed design.

The dash-dot-dash broken lines define the enlargement regions and form no part of the claimed design.
